UNITED STATES PATENT OFFICE.

THOMAS BEUCUS, OF CEDAR SPRINGS, MICHIGAN.

CARBURETER.

1,126,690.

Specification of Letters Patent.

Patented Feb. 2, 1915.

Application filed April 6, 1914. Serial No. 830,005.

To all whom it may concern:

Be it known that I, THOMAS BEUCUS, a citizen of the United States of America, residing at Cedar Springs, in the county of Kent and State of Michigan, have invented certain new and useful Improvements in Carbureters; and I do hereby declare the following to be a full, clear, and exact description of the invention, such as will enable others skilled in the art to which it appertains to make and use the same.

My invention relates to improvements in carbureters, and more particularly to carbureters for use in connection with internal combustion engines, and its object is to simplify the construction; to provide an automatic valve to control the flow of fuel and to stop off the same when the device is out of operation, and to provide the device with various new and useful features, as herein-after more fully described and particularly pointed out in the claims.

My invention consists essentially of a valve to control the flow of fuel opened by the air current flowing through the device and automatically closed when the device is out of operation; means for limiting the opening of said valve connected to the throttle valve to permit the fuel valve to open more or less as the throttle valve is opened to a greater or less extent, and in various features of construction and arrangement as will more fully appear by reference to the accompanying drawings, in which:

Figure 1 is a vertical section of a device embodying my invention, shown as when out of operation; Fig. 2 an enlarged detail showing the fuel valve opened to a moderate extent; and Fig. 3 the same with the fuel valve opened to a greater extent.

Like numbers refer to like parts in all of the figures.

1 represents a cylindrical case having a vertical axis; 2 a lateral air inlet at the bottom of the case; 3 a throttle valve to control the air inlet and direct the air downward to the bottom of the case.

4 is a lateral inlet at the bottom of the case for influx of fuel; 5 is a needle valve to limit the flow of fuel, above which valve, arranged in the axis of the case and projecting upward within the lower part of the same is a nozzle 6, within which is a vertically movable pin or needle 7, the upper part having a greater diameter than the lower part, whereby as the needle is raised the ob-

struction of the nozzle is reduced to permit increased flow of fluid from the nozzle. This pin is carried by a disk 8 having a cone valve where the pin joins the same, which valve closes the nozzle outright when no air is going through and the disk rests on the end of the nozzle.

9 is a stem extending upward from the disk to guide the same and the pin in their vertical movement. This stem is slidable freely in a vertically adjustable sleeve 10 mounted in the axis of a slide 11 vertically movable in a tubular housing 14 fitting within the case 1, and vertically adjustable therein. This housing has a conical bottom, the lower end of which is contracted to about the diameter of the disk 8 and surrounds the upper end of the nozzle 7. Extending downward around the nozzle is a conical extension of the housing forming the lower end of the housing and terminating at a distance from the base of the nozzle whereby the air is directed against the under side of the disk as it passes upward through the housing. The slide 11 is connected by a rod 12 to a throttle valve 13 located in the top of the case, whereby as the throttle valve is opened and closed the slide is simultaneously raised and lowered.

In operation, the fuel is admitted through the passage 4 and the maximum flow thereof limited by the needle valve 5. The air valve 3 is adjusted to limit a flow of air and direct the same into the bottom of the case, from whence it passes upward through the cone at the bottom of the housing and is directed thereby against the under side of the disk 8 which is raised by the air current to a greater or less extent depending upon the extent to which the throttle valve 13 is opened. The greater the air current through the device the higher the disk 8 will rise and the slide 11 will also be raised by opening the throttle valve to permit of this movement of the disk. The fuel is also permitted to flow in greater quantity by the withdrawal of the pin 7 more or less from within the nozzle, thus reducing the obstruction therein.

The jet of fuel from the nozzle is divided by the pin and valve and turned outward radially over the under surface of the disk 8 against which the air is directed. The radial movement of the fuel thus spreads and thins it and the current of air intimately minglestherewith. The mixture then passes

upward through the housing and throttle valve to the engine.

What I claim is:—

1. A carbureter, comprising a cylindrical case, lateral fuel and air inlets at the bottom of the case, a nozzle projecting upward from the bottom of the case and in the axis of the same, a housing surrounding the nozzle and adjustable in the case, a disk carrying a valve to close the nozzle, a needle projecting within the nozzle, and means for limiting the upward movement of the disk.
2. A carbureter, comprising a vertically disposed cylindrical case having an air inlet in the bottom thereof, a throttle valve in the upper part of the case, a fuel nozzle projecting from the bottom of the case and in the axis of the same, a housing vertically adjustable in the case and having oppositely extended conical portions surrounding the nozzle, a valve to close the nozzle, a needle of various diameters to obstruct the nozzle, a disk carrying the needle and valve, a stem to the disk, an adjustable sleeve for the stem, a slide adjustable in the housing and carrying the sleeve, and means for connecting the slide and the throttle valve.
3. In a carbureter, a casing having air and fuel supply inlets formed in the lower end thereof and a throttle valve in the upper end thereof, a nozzle extending axially of said casing and communicating with the fuel supply inlet, a needle valve for manually controlling the supply of fuel from the fuel inlet to said nozzle, a valve for controlling the supply of air into said casing around said nozzle, a vertically movable housing disposed within said casing and having oppositely flared inner walls, means for adjustably mounting said housing in the casing, a throttle valve in said casing, a slide disposed within the housing and operatively connected to the throttle valve, a needle valve of variable area disposed within the nozzle in axial alignment with the before-mentioned needle valve, a disk carried by the second-mentioned needle valve and disposed above the nozzle and limited in its movement by the slide and a stem extending from the needle valve and carrying the disk.
4. In a carbureter, a casing having an air inlet and a fuel nozzle in the lower end thereof and a throttle valve in the upper end thereof, a slide disposed therein, said slide having a threaded opening formed therein, a sleeve threaded in the opening of the slide, a valve controlling the fuel nozzle, a stem extending from the valve and disposed in said sleeve, and an operative connection between the throttle valve and slide.
5. The combination in a carbureter, of a casing having an air inlet and a fuel nozzle in the lower end thereof and a throttle valve in the upper end thereof, a movable member adjustable in said casing, a slide disposed in said movable member, said slide having a central threaded sleeve formed therein, a second sleeve threaded in said first sleeve, a valve stem movable in said second mentioned sleeve, a valve carried by said valve stem for engagement with the second mentioned sleeve whereby the movement of said valve will be limited and an operative connection between the throttle valve and slide.

In testimony whereof I affix my signature in presence of two witnesses.

THOMAS BEUCUS.
